UNITED STATES PATENT OFFICE.

JOHN BRIGGS, OF LOUISVILLE, KENTUCKY.

IMPROVEMENT IN TRIP-HAMMERS.

Specification forming part of Letters Patent No. 40,390, dated October 27, 1863; antedated October 11, 1863.

To all whom it may concern:

Be it known that I, JOHN BRIGGS, of Louisville, in the county of Jefferson and State of Kentucky, have invented a new and useful Improvement in Trip-Hammers; and I do hereby declare the following to be a full and exact description of the same, reference being had to the accompanying drawings, making a part of this specification, in which—

Figure 1 is a side elevation of a trip-hammer, illustrating my invention. Fig. 2 is a top view of the same. Fig. 3 is a transverse section of the same at *xx*.

Similar letters of reference indicate corresponding parts in the several views.

The subject of my invention is a trip-hammer adjustable in the height of its stroke; and the invention particularly consists, first, in an adjustable device affording a horizontal bearing for elevating the hammer in a vertical plane to any height without lateral pressure; second, in an improved construction and arrangement of cam-wheels, which serve also as fly-wheels.

In order that others skilled in the art to which my invention appertains may be enabled to fully understand and use the same, I will proceed to describe its construction and operation.

A represents a bed-plate, from which rise standards *B B C C*, in the former of which the hammer-shaft *D* is fulcrumed.

E is a shaft journaled transversely beneath the hammer-shaft in bearings on the standards *C C*, and rotated by a pulley or wheel, *F*, or other suitable means.

G G are a pair of fly-wheels, secured upon the shaft near its center with a sufficient interval between them to receive and permit the play of the hammer-shaft *D*.

H H are a pair of wedges or inclined planes, attached by their bases to a disk, *H'*, adapted to slide upon the shaft *E*. The said wedges work freely in slots *g* in the wheels *G*.

I I' are boxes fitted to slide radially out and in on the slots *g* and pressed inward against the wedges *H* by springs *J J'*.

K K are rollers journaled in the boxes *I I'*. The boxes *I'* are formed with elongations *i* in order to support the general bearings at an equal distance from the center of rotation, while both boxes rest upon the inclined faces of the wedges *H*.

Dotted lines at *d* in Fig. 1 represent an inclined or cam surface on the under side of

the hammer-shaft for gradually raising the same to any desired height by the impact of the rollers *K*, and afterward permitting it to fall suddenly, as will be hereinafter explained.

d represents an elastic substance applied to the cam *d* to take off the suddenness of impact of the rollers *K*. The wedges *H* may be moved in and out by a lever engaging in the gland *h*, or by a screw rack and pinion or other suitable means.

L represents a spring, which gradually arrests the momentum of the hammer on its upward stroke and accelerates its descent. The said spring may be of any suitable form, or may be entirely dispensed with.

D' represents the hammer-head, and *M* the anvil.

The operation is as follows: Rotation being imparted to the shaft in the direction shown by the arrow in Fig. 1, the rollers *K*, passing underneath the cam *d*, raise the hammer *D'* and permit it to fall suddenly on anything upon the anvil *M*. By moving the wedges *H* inward the rollers *K* are forced radially outward from the center, and the length and force of the stroke of the hammer thereby increased as may be necessary.

It will be observed that the parallelism and horizontality of the rollers are maintained whatever their distance from the shaft. The hammer is therefore raised upward in a vertical plane, and is caused to strike accurately and fairly. An additional and highly important advantage of the rollers *K* is the great reduction of friction against the cam *d*.

The wheels *G* serve as fly-wheels, and, being placed on each side of and close to the point at which the power is applied to the hammer-shaft, admit of the use of a lighter driving-shaft than would otherwise be practicable.

Having thus described my invention, what I claim as new therein, and desire to secure by Letters Patent, is—

1. The employment or use of parallel rollers or bearing *K*, interposed between the wedges *H* and hammer-shaft *D* for raising the latter to variable heights in a directly vertical plane.

2. The wheels *G*, secured to the shaft *E*, near the hammer-shaft *D*, and serving the combined purposes of cam and fly wheels.

Witnesses: JOHN BRIGGS.

OCTAVIUS KNIGHT,
R. H. MAYHEW.
